Attorney

UNITED STATES PATENT OFFICE.

ALBERT BISHOP CHANCE, OF CENTRALIA, MISSOURI.

CIRCUIT-CLOSING DEVICE.

SPECIFICATION forming part of Letters Patent No. 763,464, dated June 28, 1904.

Application filed April 6, 1903. Serial No. 151,367. (No model.)

To all whom it may concern:

Be it known that I, ALBERT BISHOP CHANCE, a citizen of the United States, residing at Centralia, in the county of Boone and State of Missouri, have invented certain new and useful Improvements in Circuit-Closing Devices; and I do declare the following to be a full, clear, and exact description of the invention, such as will enable others skilled in the art to

10 which it appertains to make and use the same.

My invention is an improved circuit-closing device for telephone systems, by means of which the receiver-hook is adapted to be operated to call central for a connection and for 15 automatically throwing the drop or annunciator at the central office to secure a positive "ring off" when the receiver is hung thereon.

My invention consists in the construction, combination, and arrangement of devices 20 hereinafter described and claimed.

In the accompanying drawings, Figure 1 is 25 an elevation, partly in section, of a circuit-closing or switch device embodying my invention. Fig. 2 is a detail view, on an enlarged scale, of one of the contact-pieces.

The telephone switch-hook P is provided 30 with an obliquely-disposed conducting-cam G, and the switch-spring E has a similarly-disposed conducting-cam H, insulated on its lower side, as at I. A suitable spring a is provided for the switch-hook to raise the latter.

The switch-spring or switch-spring arm E is disposed substantially at right angles to the switch-hook, extends across one side thereof, 35 and its obliquely-disposed contact-cam I is in the path of the switch-hook contact-cam G. The free end of the switch-spring arm extends beyond its contact-cam.

A spring L, which serves to prevent casual 40 vibration of the switch-spring, engages the latter at its extended free end, as shown.

By the provision of the extended free end 45 of the switch-spring arm extending beyond its contacting point and of the spring L bearing against said end of the switch-spring arm, the operation of the device is rendered very much more certain than would otherwise be the case, and the springs employed may be of comparatively slight strength, so as not to

interfere with the operation of the switch- 50 hook.

When the receiver is removed from the switch-hook, the latter moves upwardly under the impulse of its spring a, and its conducting-cam G engages and passes the insulated side of the cam H, fastened on the switch-spring E, so that no current passes, because 55 electrical contact is not established.

A signal to central for a connection may be 60 made by removing the receiver, allowing the switch-hook to move upwardly, then depressing the switch-hook and releasing the same. When the switch-hook is depressed, its cam G engages the metallic conducting side of the cam H of the battery switch-spring E, thereby 65 establishing momentarily a battery-circuit through the line and the annunciator at central to cause the drop to be released. By the provision of the insulator on one side of the contact-cam of the battery switch-spring E a 70 signal to central to disconnect is prevented, as will be understood. A signal to central to disconnect is transmitted by the next descent of the switch-hook when the receiving-telephone of the subscriber is hung thereon. 75

Having thus fully described my invention, what I claim as new, and desire to secure by Letters Patent, is—

In combination with a movable switch-hook having an obliquely-disposed contact-cam projecting from one side thereof, a switch-spring arm disposed substantially at right angles to the switch-hook extending across one side thereof having an obliquely-disposed contact-cam insulated on one of its contact sides projecting therefrom and in the path of the switch-hook contact-cam, the free end of such switch-spring arm extending beyond its contact-cam and a spring to prevent casual vibration of the switch-spring and engaging the latter at its 85 extended free end.

In testimony whereof I have hereunto set my hand in presence of two subscribing witnesses.

ALBERT BISHOP CHANCE.
